OIL BURNER

Mark Baker and Sven A. Hallgren, Worcester,
Mass., assignors, by mesme assignments, to
Boston Machine Works Company, a corpora-
tion of Massachusetts

Application July 21, 1932, Serial No. 623,828

5 Claims. (Cl. 158—87)

This invention relates to oil burners, and more particularly to oil burners provided with perforated sleeves arranged to form one or more annular chambers in which combustion takes place. It has heretofore been proposed to provide burners of this type with a central vaporizing chamber to which the oil is supplied and from which the oil vapor is conducted ultimately through radial passages leading to the combustion chambers. The prior constructions have however been subject to certain difficulties in actual operation, or have been complicated and expensive to manufacture. With some arrangements there is a considerable danger of explosion in the event the burner is in charge of an unskilled operator. With other constructions the arrangement for conducting vapor from the vaporizing chamber to the combustion chamber has resulted in considerable back pressure or has not caused an even and continuous flow of vapor. With other constructions, undesirable carbon deposits form in parts of the burner which are inaccessible for cleaning. Still other constructions are difficult to light, or will not operate satisfactorily over a sufficiently wide range of fuel burning rates, or are inefficient and wasteful of oil. In many cases, prior burners are easily flooded with oil and cause damage to other property and danger of fire.

It is accordingly one object of the invention to overcome these difficulties, and to provide a simple and inexpensive oil burner which is capable of safe and efficient operation at both high and low combustion rates. It is a further object of the present invention to provide an oil burner so constructed that vapor will be conducted from the vaporizing chamber to the combustion chamber in an even and continuous flow.

It is a further object of the invention to provide an oil burner so constructed that carbon deposits are largely eliminated, and such deposits as do occur can be readily removed.

It is a further object to provide an oil burner which can be easily primed and lighted by an unskilled operator without danger of flooding.

With these and other objects in view, as will be apparent to those skilled in the art, the invention resides in the combination of parts set forth in the specification and covered by the claims appended hereto.

Referring to the drawing illustrating one embodiment of the invention and in which like reference numerals indicate like parts,

Fig. 1 is a vertical section through an oil burner and its associated oil feeding apparatus, the section being taken on the line 1—1 of Fig. 2;

Fig. 2 is a top plan view of the burner base, all other parts having been removed therefrom;

Fig. 3 is a section on the line 3—3 of Fig. 1;

Fig. 4 is an enlarged detail showing the construction of a supporting lug;

Fig. 5 is a plan view of a portion of the central cover plate; and

Fig. 6 is a perspective view showing the bottom of the priming disk.

The embodiment illustrated comprises a base 10 of suitable material, such as cast iron, shaped to provide inner and outer concentric annular fuel grooves 11 and 12 respectively. These grooves are open at the top, and they are connected by four equally spaced radial passages 14. Four concentric perforated cylindrical sleeves 15 are mounted on the base 10 and arranged to form two annular combustion chambers 17 and 18 located directly above and in communication with the grooves 11 and 12 respectively. The sleeves 15 are preferably comparatively thin and formed from a suitable high heat resisting steel.

The base 10 is preferably shaped to provide a central annular groove 20 which is concentric with the fuel grooves 11 and 12 and smaller in diameter. The groove 20 is likewise open at the top, and it is connected to the inner fuel groove 11 by means of four radial passages 21 which are shown aligned with the passages 14. The outer wall 22 of the central groove 20 as illustrated extends slightly above the tops of the fuel grooves, while the inner wall 23 of the central groove extends for a considerable distance upwardly and preferably terminates in a horizontal plane located more than half-way up the sleeves 15. A horizontal wall 25 extends across within the cylindrical wall 23 and is spaced downwardly from the top edge thereof, thus providing a central vaporizing chamber in the form of a cup 26 which is open at the top. In order to conduct the oil vapor which is generated in the cup 26 to the central groove 20, from whence it may flow to the fuel grooves, we provide a member 27 shaped as an inverted cup mounted on the wall 22 and form-

ing a chamber enclosing the vaporizing cup. The member 27 is spaced both vertically and laterally from the vaporizing cup and the portions of the wall 23 below the cup, so as to provide an annular 5 passage for the vapor from the cup 26 downwardly to the groove 29 and the passages 21 and 14. As will be seen in Fig. 1 the bottom of the inverted cup 27 overlies the vaporizing chamber formed by the cup 26. The wall 22 is preferably 10 provided with a pair of outwardly projecting pins 29 which engage bayonet slots 30 in the lower portion of the member 27 to hold the parts in assembled relation, while permitting ready separation thereof when necessary. The member 27 is preferably 15 formed of thin, high heat resisting steel.

The vaporizing cup 26 is supplied with oil by gravity from a reservoir 32, and the oil in the reservoir is maintained at a constant level slightly below the elevation of the upper edge of the cup, 20 over which the vapor must pass to enter the vapor passage. One suitable means for maintaining the desired oil level comprises an inverted bottle 33 of well-known construction which forms a barometric oil feeding device. These parts are 25 shown on a greatly reduced scale as compared to the burner itself. A conduit or pipe 34 leads from the reservoir 32 to the cup 26, preferably entering directly and vertically into the center of the bottom wall 25 thereof. A manually operable 30 valve 36 in the pipe 34 serves to control the rate of oil flow. We preferably provide a T 37 in the oil pipe located with the run of the T vertical and directly beneath the vaporizing cup. A plug 38 is provided in the bottom of the T. By first removing this plug, it is possible to insert a brush or other tool and thus clean the vertical section 35 of the pipe.

It is desirable to restrict the annular discharge slots at the top of the combustion chambers 17 and 18, as it has been found that this results in more perfect combustion and the production of a clean blue flame. We preferably provide this restriction by means of a frusto-conical portion or flange 40 at the top of each perforated sleeve 45 15, each flange 40 being arranged to slope upwardly and to extend over the adjacent annular combustion chamber. The flanges 40 are preferably formed integral with the sleeves by a rolling process. They not only provide the desired restriction at the top of the combustion chambers, but also serve to stiffen and strengthen the sleeves 15, thus reducing the possibility of warping of these parts from the heat, or damage from 50 careless handling during shipment or installation.

55 In order to compel the air which flows upwardly between the radial passages 21 to pass through the inner perforated sleeve 15 into the combustion chamber 17, we utilize a circular plate 42, which is preferably formed of thin, high heat 60 resisting steel and provided with radial strengthening ribs 43 pressed therein. The plate 42 fits closely within the inner sleeve and preferably rests upon lugs 44 on the sleeve and near the top thereof. These lugs may be formed integral with the sleeve by forcing a small portion of the metal inwardly, as indicated in detail in Fig. 4. An annular plate 46 is provided between the two combustion chambers to compel air which flows upwardly between the radial passages 14 to pass 65 through the perforated sleeves. This plate 46, which is preferably formed of the same material as plate 42, may rest on lugs 47 formed near the tops of the sleeves and similar to the lugs 44. This provides a construction which is simple and inexpensive to manufacture. The assembled

burner is rigid and unlikely to become distorted, yet the various parts can be easily taken apart if necessary.

In order to place the burner in operation, it is necessary to provide means for heating the oil in the cup 26, thus starting the formation of the oil vapor. For this purpose we have illustrated an annular wick 50 of suitable material, such as asbestos, which is mounted in the inner fuel groove 11. This wick is provided with notches 51 at the bottom in line with the passages 21 and 14, so as not to obstruct the flow of the vapor. Since the oil level in the reservoir 32 is below the top of the vaporizing cup 26, it is impossible to saturate the wick 50 by opening the valve 36. We accordingly provide means for priming the burner by forcing oil from the cup 26 upwardly and over the edge of the cup. For this purpose we preferably utilize a thin circular disk 53 mounted within the vaporizing cup and provided with an upwardly 20 extending stem 54, which is free to slide through openings in the member 27 and the plate 42. The stem 54 may be provided with a ring 55 at its upper end which forms a handle. The disk 53 is preferably slightly smaller in diameter than the 25 vaporizing cup, and provided with several small projecting portions 56 on its lower surface which rest upon the bottom wall 25 of the cup. With this construction the oil may flow into the cup freely. To prime the burner it is merely necessary to raise the disk 53 quickly by means of the handle 55, whereupon a quantity of oil will be forced over the edge of the cup. The pins 29 prevent any accidental dislodgment of the member 27 as a result of the disk 53 striking thereagainst.

The operation of the invention will now be apparent from the above disclosure. The wick 50 is saturated by raising the handle 55, and the oil in the wick is ignited by inserting a lighter downwardly into the inner combustion chamber 17. After a few minutes the burner will become hot and the oil in the cup 26 will begin to vaporize. The oil vapor will first ascend into impingement with the bottom of the inverted cup 27 and will then travel therefrom downwardly through the annular passage and superheating chamber formed by the wall 23 and the inverted cup 27, through the radial passages 21 to the inner fuel groove 11, and thence through the radial passages 14 to the outer fuel groove 12. From the grooves 11 and 12 the vapor will ascend into the combustion chambers 17 and 18, where it will mingle with the air flowing into these chambers through their perforated walls and produce efficient combustion.

Since the vaporizing cup 26 is located high up in the burner and in a zone of comparatively high temperatures, it is possible to operate the burner at very low combustion rates when desired, and yet there will be sufficient heat transmitted to the vaporizing cup to ensure the generation of the necessary quantity of vapor. The combustion rate is controlled by means of the valve 36, but it is impossible for a careless operator to flood the burner even though the burner is cold and the valve is opened wide. Except when the burner is primed for starting, nothing but vapor is burned, and no liquid oil reaches the fuel grooves. Hence the combustion is very rapid and efficient, and no carbon deposits are formed in the various passages of the burner. The vapor is free to escape as rapidly as it forms, so that the vapor pressure cannot increase to any appreciable extent, and there is consequently no 75

danger of explosions from this cause. The member 27 becomes very hot, and not only radiates heat to the vaporizing cup but also conducts heat to the vapor flowing downwardly from the cup. 5 This superheats the vapor and adds to the efficiency of combustion.

Having thus described our invention, what we claim as new and desire to secure by Letters Patent is:

10 1. An oil burner comprising means including two perforated sleeves providing an annular combustion chamber, a central vaporizing chamber, means providing a passage for vapor leading from the vaporizing chamber to the lower portion of the combustion chamber, an oil reservoir, means to maintain oil in the reservoir at a level below the elevation of the entrance to the vapor passage, a conduit leading from the reservoir to the vaporizing chamber and entering said chamber at an elevation below said oil level, and manually operable means to force oil from the vaporizing chamber into the vapor passage and thus prime the burner.

2. An oil burner comprising means including two perforated sleeves providing an annular combustion chamber, a central vaporizing chamber, means providing a passage for vapor leading from the vaporizing chamber to the lower portion of the combustion chamber, an oil reservoir, means to maintain oil in the reservoir at a level below the elevation of the entrance to the vapor passage, a conduit leading from the reservoir to the vaporizing chamber and entering the chamber at an elevation below said oil level, a member mounted in the vaporizing chamber below the oil level, and means for raising said member manually, whereby oil may be forced into the vapor passage to prime the burner.

3. An oil burner comprising means including two perforated sleeves providing an annular combustion chamber, a central vaporizing cup open at the top, means providing a passage to conduct vapor from the cup to the lower portion of the combustion chamber, an oil reservoir, means to maintain oil in the reservoir at a level below the elevation of the top of said cup, a conduit leading from the reservoir to the vaporizing cup and entering the cup at an elevation below said oil level, a substantially horizontal disk mounted in the cup below the oil level, and means for raising said disk manually, thereby

forcing oil over the edge of the cup into the vapor passage to prime the burner.

4. An oil burner comprising means forming an annular fuel groove open at the top, two perforated cylindrical sleeves providing an annular combustion chamber located above and in communication with the groove, a central circular vaporizing cup open at the top, the edge of the cup being higher than the bottom of the fuel groove, means providing a passage to conduct vapor from the cup to the fuel groove, an oil reservoir, means to maintain oil in the reservoir at a level below the elevation of the edge of the cup, a conduit leading from the reservoir to the vaporizing cup and entering the cup below the oil level, a circular disk mounted in the cup and substantially equal to the cup in diameter, and a stem extending upwardly from the disk, whereby the disk may be lifted manually and oil forced over the edge of the cup into the vapor passage to prime the burner.

5. An oil burner comprising means forming an annular fuel groove open at the top, two perforated cylindrical sleeves providing an annular combustion chamber located above and in communication with the groove, means including inner and outer walls forming a central annular groove open at the top which is concentric with and smaller in diameter than the fuel groove, radial passages connecting the grooves, a wall extending across within the inner wall and spaced downwardly from the top edge thereof to provide a vaporizing cup which is open at the top, an oil reservoir, means to maintain oil in the reservoir at a level below the elevation of the edge of the cup, a conduit leading from the reservoir to the vaporizing cup and entering the cup below the oil level, an inverted cup mounted over the vaporizing cup and supported on the outer wall, said inverted cup being arranged to direct vapor from the vaporizing cup downwardly, a disk mounted in the vaporizing cup below the oil level, a stem projecting upwardly from the disk through the inverted cup, whereby the disk may be lifted manually to prime the burner, and means to fasten the inverted cup to the outer wall, said means including a pin on one of these parts which engages a bayonet slot in the other part.
